UNITED STATES PATENT OFFICE.

WILLIS C. WARD, OF ORCHARD LAKE, MICHIGAN.

BOAT-SAIL.

1,348,912.

Specification of Letters Patent. Patented Aug. 10, 1920.

Application filed December 5, 1919. Serial No. 342,576.

To all whom it may concern:

Be it known that I, WILLIS C. WARD, a citizen of the United States of America, residing at Orchard Lake, in the county of Oakland and State of Michigan, have invented 5 certain new and useful Improvements in Boat-Sails, of which the following is a specification, reference being had therein to the accompanying drawings.

- 10 The invention relates to sails designed for use on boats and it is the object of the invention to obtain a stronger, more durable and more easily manipulated construction than the ordinary canvas sail. To this end 15 the invention consists; first, in a sail formed of rigid material; second, in a construction having a peripheral rigid frame with a metal sheet extending thereacross; third, in a construction which will automatically unload or spill the wind when subjected to an 20 over-pressure; fourth, the various specific features of construction as hereinafter set forth.

In the drawings:

- 25 Figure 1 is a diagrammatic plan view showing the sail as applied to a boat;

Fig. 2 is a sectional side elevation of the sail and its supporting frame;

Fig. 3 is a transverse section.

- 30 My improved sail is preferably of an elliptical or oval form and is provided with a peripheral rigid frame A, across which is extended preferably a sheet metal member B. The frame A is provided at its opposite ends with trunnions C which are journaled in a bifurcated supporting frame D of a form to provide clearance for the swinging of the frame A. The frame D is mounted upon a vertical pivot pin E, which 35 is journaled in a bearing F in a mast G. The pivot pin E is preferably hollow to permit of the passage of a rope, or other flexible connection, H which is attached at one end to the frame A and at its opposite 40 end is yieldably anchored as by the spring I. Suitable sheaves J are arranged for the rope or flexible connection to travel over.

- 45 The trunnions C on the frame A are at one side of the central longitudinal axis of 50 said frame, so that unequal areas are exposed on opposite sides of the axis of said trunnions and thus when exposed to wind pressure, the pressure on the larger area will over-balance that on the smaller area 55 and will move the sail into an inclined position, its angle depending upon the total

wind pressure and the resistance of the spring I. The spring I is set at such a tension as to normally hold the sail in a position favorable for receiving wind pressure, 60 but upon an abnormal pressure the frame A will turn to an angle where the wind will be spilled.

The pivot bearing E is also preferably arranged at one side of the vertical central 65 axis of the frame A so as to expose unequal areas to the wind pressure, the smaller area being forward and the larger area in rear of the mast. The rear end of the frame D is attached to a rope, or other flexible 70 securing means, K which is controlled in the same manner as the usual boat sail.

In use, the sail, when exposed to limited wind pressure, will assume a position in the plane of the frame D where it will present 75 its entire area to the action of the wind. As soon, however, as the pressure increases beyond a predetermined limit, the sail will automatically turn to an angle to prevent further increase in pressure. This action is entirely independent of the adjustment of the sail about the vertical axis of the mast and the operator can control the position by the rope K in the usual manner.

What I claim as my invention is:

1. A boat sail comprising a sheet of rigid material, and an adjustable frame in which said sheet is mounted.

2. A boat sail comprising a rigid peripheral frame, a sheet extending across and secured to said frame, and a mounting in which said frame is adjustably secured.

3. A boat sail comprising a rigid peripheral frame, a sheet extending thereacross and secured thereto, a frame in which said first-mentioned frame is pivotally secured to be adjustable about a longitudinal axis, and a mounting for said last-mentioned frame permitting of adjustment about a vertical axis.

4. A boat sail comprising a rigid peripheral frame, a sheet extending thereacross and secured thereto, a bifurcated frame extending longitudinally of said first-mentioned frame and embracing the same, a pivotal connection between said frames permitting the adjustment of the first-mentioned frame about a longitudinal axis having unbalanced areas on opposite sides thereof, and means for yieldably holding 110 the adjustable frame against unbalanced wind pressure.

5. A boat sail comprising a frame and a sheet extending thereacross, a pivotal mounting for said frame located to expose unbalanced areas on opposite sides of the 5 axis thereof, and means for resisting rotation of said frame under unbalanced wind pressure adapted to yield at a predetermined limit of pressure.

6. In a boat, the combination with a mast, 10 of a bifurcated frame pivotally mounted on said mast, an annular frame pivotally secured in said bifurcated frame to be rotatable about a longitudinal axis, said axis being at one side of the center of the frame, 15 a sheet extending across said annular frame and exposed to wind pressure, and means for holding said annular frame in the plane of

said bifurcated frame yieldable when said sheet is exposed to a predetermined pressure. 20

7. A boat sail comprising an oval peripheral frame, a sheet extending thereacross and secured thereto, a bifurcated frame extending longitudinally of said oval frame and embracing the same, a pivotal connection between said bifurcated frame and oval frame arranged at one side of the central longitudinal axis of said oval frame, a mast, and a pivotal connection between said bifurcated frame and mast extending vertically 25 at one side of the longitudinal center of said oval frame. 30

In testimony whereof I affix my signature.
WILLIS C. WARD.
